UNITED STATES PATENT OFFICE

140,245

DESIGN FOR A CIGAR CANISTER DISPLAY UNIT

Robert B. Wemyss, Louisville, Ky.

Application October 14, 1944, Serial No. 115,769

Term of patent 7 years

(Cl. D80—9)

To all whom it may concern:

Be it known that Robert B. Wemyss, a citizen of the United States, residing in Louisville, county of Jefferson, State of Kentucky, has invented a new, original, and ornamental Design for a Cigar Canister Display Unit, of which the following is a specification, reference being had to the accompanying drawing, forming part thereof.

The figure is a perspective view of a cigar canister display unit showing my new design, the top of one canister being shown in open position.

I claim:

The ornamental design for a cigar canister display unit, substantially as shown.

ROBERT B. WEMYSS.
